US0D1082614S

(12) **United States Design Patent** (10) **Patent No.:** **US D1,082,614 S**
(45) **Date of Patent:** **** Jul. 8, 2025**

(54) **ALL-TERRAIN VEHICLE**

(71) Applicant: **SEGWAY TECHNOLOGY CO., LTD.**, Changzhou (CN)

(72) Inventor: **Hao Xie**, Changzhou (CN)

(73) Assignee: **SEGWAY TECHNOLOGY CO., LTD.**, Changzhou (CN)

(**) Term: **15 Years**

(21) Appl. No.: **29/989,351**

(22) Filed: **Feb. 12, 2025**
